PIATT M. ORLOPP, OF INDIANAPOLIS, INDIANA.

GASEOUS-FLUID MIXER.

1,088,034.

Specification of Letters Patent.

Patented Feb. 24, 1914.

Application filed January 13, 1913. Serial No. 741,755.

To all whom it may concern:

Be it known that I, PIATT M. ORLOPP, a citizen of the United States, and a resident of Indianapolis, county of Marion, and 5 State of Indiana, have invented a certain new and useful Gaseous-Fluid Mixer; and I do hereby declare that the following is a full, clear, and exact description thereof, reference being had to the accompanying 10 drawings, in which like letters refer to like parts.

The object of this invention is to provide improved means for causing the admixture of hydrocarbon fluid and air after they leave 15 a carbureter and as they enter or pass through the intake pipe leading from the carbureter to the manifold or engine cylinders. In devices of the kind heretofore, the difficulty has been that the intake pipe would 20 become "loaded." By this is meant that there would be a heavy deposit of the hydrocarbon, in globules, on the inner wall of the intake pipe and the air would not mix effectively, but would point away from and pass 25 said globules. Heretofore, the hydrocarbon instead of mixing with the air and going into the cylinder of the engine, has, to too great an extent, been deposited on or has adhered to the wall of the intake pipe and 30 accumulated there until it is in a mixture of the desired proportion of hydrocarbon, but has interfered materially with the operation of the device.

The chief feature of my invention consists 35 in arranging a screen in the intake pipe at an inclination and to a greater or less degree inclined in or parallel with the direction of movement of the air after it passes the throttle valve so that the hydrocarbon 40 particles could deposit only on the screen and the deposit, by reason of the inclination of the screen, would be substantially uniform and the air, would, therefore, come in a direct and substantially uniform contact 45 with the screen and force itself through the screen and thus take up constantly the particles of hydrocarbon, as it passes through the screen, so as to prevent any excessive deposit of hydrocarbon and to cause the hydrocarbon 50 to be taken up with the air and carried into the cylinders.

The nature of the invention will be understood from the accompanying drawings and the following description and claims.

55 In the drawings, Figure 1 is a side eleva-

tion of a carbureter with the upper part thereof and the lower part of the intake pipe in central vertical section, parts being broken away. Fig. 2 is a perspective view of the screen and means for supporting the same. Fig. 3 is a central vertical section through the outlet pipe of the carbureter and intake pipe, parts being broken away. Fig. 4 is the same with the screen included and showing the passage of air and fuel 60 therethrough.

A carbureter 10 of any type may be employed, having an outlet pipe 11 secured to an engine intake pipe 12 by screws 13. A throttle valve 14 may be placed in either the outlet pipe 11 or intake pipe 12, as desired.

My invention consists in placing a screen 15 and the means for supporting it in the intake pipe beyond or above the throttle valve, whether the latter be in the intake pipe or the outlet pipe from the carbureter. The means for supporting the screen 15 consists of a tube 16 with an annular collar 17 on one end adapted to lie between the flanges on the ends of the pipes 11 and 12 and have the screw 13 to pass through so as to clamp the collar and pipe 17 securely in place in the pipe 12. The other end of the pipe 16 is cut at an angle of about forty-five degrees and the screen 15 secured thereon so that it will be inclined at said angle. Preferably the intake pipe should be bored out to make an annular recess 18 of about the same thickness as the pipe 16 for the purpose of receiving and securing said pipe 16. That 70 leaves the passageway through the pipes 11, 16 and 12 smooth and of the same diameter, which is important. Furthermore, the tube 16 is so arranged in the intake pipe with reference to the throttle valve, that the lower 75 end of the screen 15 will be located on the same side of the passageway at which the major portion of the mixture passes the throttle valve. In other words, the throttle valve opens toward the lower end of the 80 screen or the end nearest the throttle valve and deflects nearly all of the mixture to that side of the passageway so that it first strikes the lower part of the screen and travels up the underside of the screen to a greater or 85 lesser extent so that the passage of air or mixture through the parts of the screen will be substantially equal or uniform, as indicated in Fig. 4. This will cause small particles of the fuel to lodge on the screen, but 90

95 100 105 110

the air will constantly sweep through the screen adjacent said particles and take them almost as soon as they are deposited. This will cause the uniform and satisfactory admixture of the elements of the mixture and carry the fuel into the cylinder and prevent the fuel accumulating in the intake pipe. Very little fuel can accumulate in the tube 16 below the lower part of the screen because it will be taken up by the great sweep of air over that surface. Not very much accumulates on the other side of the pipe 16, because not very much mixture passes the valve at that side. Probably more than four-fifths of the mixture on the average is deflected past the other side of the valve.

Fig. 3 illustrates the means heretofore employed and the manner in which the fuel accumulates in the intake pipe and "loads" it. The object of this invention is to avoid that result, that "loading".

I claim as my invention:

1. A gaseous fluid mixer including a conduit, a tilting throttle valve therein, and a screen located in said conduit immediately beyond the valve and in an oblique position.

2. A gaseous fluid mixer including a conduit, a tilting throttle valve therein, and a screen located in said conduit immediately beyond the valve and in an oblique position,

the valve and screen being relatively arranged so that the valve deflects the gaseous fluid toward the nearer part of the screen.

3. A gaseous fluid mixer including a conduit having a straight portion, a throttle valve therein, a screen holding pipe secured in said conduit in the straight portion thereof beyond the throttle valve with its inner end cut off obliquely, and a screen secured on said inclined end of said inserted pipe.

4. A gaseous fluid mixer including a pipe having a radial flange, a second and continuing pipe having a straight portion bored out to provide a recess in the inner wall thereof, a throttle valve in one of said pipes, another pipe within the recess in the straight portion of said second pipe and having a radial flange located between the two flanges of said pipes, screws extending through all of said flanges for clamping them together, the inner end of said inserted pipe being cut off obliquely, and a screen secured to the inner end of said inserted pipe.

In witness whereof, I have hereunto affixed my signature in the presence of the witnesses herein named.

PIATT M. ORLOPP.
